UNITED STATES PATENT OFFICE.

FREDERICK W. KING, OF NEW YORK, N. Y., ASSIGNOR TO JULIUS KING OPTICAL COMPANY, A CORPORATION OF NEW YORK.

GOOGLES.

1,405,787.

Specification of Letters Patent.

Patented Feb. 7, 1922.

Application filed November 1, 1919. Serial No. 335,117.

To all whom it may concern:

Be it known that I, FREDERICK W. KING, a citizen of the United States, residing at the city of New York, in the county of New York and State of New York, have invented 5 certain new and useful Improvements in Goggles, of which the following is a full, clear, and exact description.

My invention has particular application to 10 goggles for use in industrial plants to protect the eyes of the wearer against injury from flying particles and the like. The first consideration with such goggles is the feature of safety, and it is therefore desirable 15 that the eye rims or cups conform to the contour of the features in such a way as to completely enclose the eyes. For industrial goggles of this character metal is the cheapest as well as the strongest and altogether 20 the most satisfactory material which can be used for the rims, and an object of my invention is to provide a sheet metal construction for such rims or eye cups which will completely enclose and protect the eye, and 25 which will be sufficiently light for comfort and which will afford the desired ventilation without impairing the protective quality of the goggles.

In accordance with my invention I pro- 30 vide sheet metal eye cups of substantial depth and preferably shaped to conform to the features, and provided with ventilating openings for substantially three-quarters of its circumference, the upper inside quadrant being imperforate, and I combine there- 35 with a pivoted foraminous shield member which is adapted to cover the openings in the outer half of the cup and screen them from flying particles. The features of the 40 wearer sufficiently cover the openings in the lower inside quadrant of the cup to shield them from flying particles, and the eye is thereby completely protected while the openings make the cups sufficiently light and afford ample ventilation.

I shall now describe the illustrated em- bodiment of my invention and shall there- 45 after point out my invention in claims.

Figure 1 is a bottom plan of a pair of 50 goggles embodying my invention;

Fig. 2 is a vertical sectional elevation thereof on line 2—2 of Fig. 1; and

Fig. 3 is an end view thereof.

In the illustrated construction the rims 55 for the lenses 1 are sheet metal cup members

2 shaped on their inner edge to conform more or less closely to the features of the wearer. The eye cups are connected by a suitable flexible bridge member 3 and also preferably by an additional flexible strength- 60ening brace 4. The nose piece 4' is disposed between the lenses some distance below the bridge member 3, and is attached thereto by a flexible post 5 which extends upwardly some distance above the bridge member and 65 thence turns downwardly and is attached to the upper edge of the bridge member, the looped portion of the post being thereby disposed above the line of vision, thus conforming with the construction of my prior 70 Patent No. 1,204,161.

To lighten the eye cups and at the same time to provide the desired ventilation, I form several openings 6 in the wall of each eye cup 2, which series of openings extends 75 for about three quarters of the circumference of the cups, the upper inside quadrant being preferably left imperforate for the reason that the features of the wearer would not protect that quadrant.

Foraminous semi-circular shields 7 with a suitable sheet metal binding or edging are pivoted to the eye cups on the central vertical axis of the cups, and are notched at the middle of their bottom edge to receive the 85 end pieces 8 to which the temples 9 are hinged, and thereby permit the shields to occupy a position on the eye cups when the goggles are worn sufficiently far down to cover the openings 6 in the outer half of the 90 cups, the openings being at least partially exposed through the foraminous material, as appears in Figure 3. The nose and the cheeks of the wearer will guard the openings 6 in the lower inside quadrant.

It is obvious that various modifications may be made in the construction shown in the drawings and above particularly de- 100 scribed within the principle and scope of my invention.

I claim:

1. For goggles or the like, a substantially cylindrical eye cup composed of sheet metal and provided circumferentially with venti- 105 lating openings, the upper inside quadrant being imperforate, and a semi-circular shield member pivoted substantially in the vertical diametral axis of the eye cup and adapted to cover the openings in the outer half thereof.

110

2. For goggles or the like, a substantially cylindrical eye cup composed of sheet metal and provided circumferentially with ventilating openings, the upper inside quadrant 5 being imperforate, and a semi-circular shield member of foraminous material pivoted substantially in the vertical diametral axis of the eye cup, and having its bottom edge shaped to enable the foraminous material to 10 cover the openings in the outer half thereof.

3. For goggles or the like, a substantially cylindrical sheet metal eye cup having the

inner portion shaped to conform to the features of the wearer and provided circumferentially with ventilating openings, and 15 a semi-circular shield member of foraminous material pivoted substantially in the vertical diametral axis of the eye cup, and having its bottom edge shaped to enable the foraminous material to cover the openings in the 20 outer half thereof.

In witness whereof, I subscribe my signature.

FREDERICK W. KING.
